UNITED STATES PATENT OFFICE.

WALTER ALLEN JACOBS, OF ADAMANT, VERMONT.

PASSENGER-CAR.

No. 844,133.

Specification of Letters Patent.

Patented Feb. 12, 1907.

Application filed February 27, 1906. Serial No. 303,187.

To all whom it may concern:

Be it known that I, WALTER ALLEN JACOBS, a citizen of the United States, residing at Adamant, in the town of Calais, in the county of Washington and State of Vermont, have invented new and useful Improvements in Passenger-Cars, of which the following is a specification.

The invention relates to an improvement in passenger-cars designed primarily for street-railway service and comprehending specifically a car constructed to be readily converted into the open or closed type.

The main object of the present invention resides in the production of a car constructed to permit either a transverse or longitudinal arrangement of seats, as may be desired, with the particular type of car, thereby providing the conventional arrangement of seats with both the open and closed type.

A further object of the invention is the provision of seats provided with telescopic sections and whereby the increased seating capacity of the open car is provided for in converting the structure from a closed car.

A further object of the invention is the provision of means by which the sides of the car may be closed or opened, as necessary, in the particular type of car desired.

A further object of the invention will be apparent from the following description, taken in connection with the accompanying drawings, in which—

Figure 1 is a horizontal section through a car constructed in accordance with my invention, the line of section being just above the seats and the car shown as of the open type. Fig. 2 is a similar view showing the car converted to the closed type. Fig. 3 is a view in elevation of one of the seats of the car, showing it arranged as an open car. Fig. 4 is a section of the same on line 4 4 of Fig. 3. Fig. 5 is a rear elevation of one of the central seats of the car when in use for an open car. Fig. 6 is a section on line 6 6 of Fig. 5. Fig. 7 is a view in elevation, showing one end seat constructed in arrangement in the open-car type. Fig. 8 is a section of the same on line 8 8 of Fig. 7. Fig. 9 is a section of the same on line 9 9 of Fig. 7. Fig. 10 is a plan of the opposite end seat for the open type construction. Fig. 11 is a front elevation of the same. Fig. 12 is a vertical central section of the same, the seat being shown in folded position in dotted outline. Fig. 13 is

an end elevation of an auxiliary seat necessary for the closed type of car, but shown in Fig. 7 as concealed beneath an end seat in the open type of car. Fig. 14 is a detail perspective illustrating the connection between the telescoping back and the end hinge therefor. Fig. 15 is a rear elevation of one of the seat-backs, showing means for holding same in operative position. Fig. 16 is an enlarged sectional view illustrating the telescopic connection between the said sections, the sections being shown extended. Fig. 17 is a section on line 17 17 of Fig. 16. Fig. 18 is a view in elevation, illustrating the sliding-panel arrangement for closing the sides of the car. Fig. 19 is a section through one of the roof-standards of the car, illustrating the arrangement of the sliding panels relative to said standard. Fig. 20 is a perspective of one of the sliding panels. Fig. 21 is a broken section transverse the car, taken through the sliding panels, showing the panels elevated to provide the open type of car. Fig. 22 is a similar view showing the panels lowered to provide the closed type of car. Fig. 23 is an enlarged broken sectional view illustrating the connection between the broken ends of two of the panels. Fig. 24 is a transverse section of the car constructed in accordance with my invention, showing the same in use as an open car. Fig. 25 is a broken enlarged elevation showing the cam connection for permitting independent vertical movement of the seats. Fig. 26 is a plan view of one of the cam-sections.

Referring particularly to the drawings, my improved car, so far as the framing thereof is concerned, may be of any desired construction, it being understood that, aside from the seat structure and side panel structure, the particular arrangement or details of the car frame or body are immaterial so far as the present invention is concerned, and I contemplate the use of any type desired. For the purposes of the present invention, however, the car-body comprises the floor 1, mounted upon the usual longitudinal wheels 2, to which are secured the folding longitudinally-arranged side steps 3, the body being supported upon the usual truck-frames 4. The car-body has the usual ends 5, provided with central sliding doors 6 and beyond said ends with a platform 7, upon which is supported the usual controlling and operating mechanism. The body is covered by any de-

sired type of roof 8, supported from the floor and wheels 2 by roof-standards 9, which are of a particular construction, to be later described, it being understood, however, that these standards are arranged in vertical spaced parallel relation, as is usual in car constructions.

The essential feature of the present invention resides in the construction of seats for said car by which the car may be converted to the usual open type, having seats extending entirely across the body of the car, or may be converted into a car of the closed type, in which the seats extend longitudinally of and in proximity to the side walls of the car.

Referring particularly to Fig. 1, wherein the seat arrangement is shown to provide a car of the open type, it will be noted that the end seats of the car differ in specific construction from each other and from the remainder of the seats and that one of the seats next to one of the end seats is also of a particular distinctive construction, the remaining seats of the car being practically identical with each other. For the purposes of the following description the forward end seat will be indicated by 10, the rear end seat by 11, the particular seat next the seat 10 by 12, and the remaining seats of the car, which are of duplicate construction, by 13.

The end seat 10, for convenience herein-after referred to as the "forward" end seat, is illustrated particularly in Figs. 1, 10, 11, and 12, wherein it is shown as comprising three sections 14, 15, and 16, each approximately one-third the length of the seat, the central section 15 telescoping in the section 16 when converting the car to a closed car. It will be noted that the end seat 10 extends entirely across the car and that the central section 15 when extended projects across the entrance-opening closed by the forward door 6, so that when this section 15 is telescoped within the section 16 the doorway is unobstructed and may be used for the ordinary purpose.

The construction of the end seat to permit the telescopic action referred to is illustrated particularly in Figs. 16 and 17, such telescopic connection being the preferred form used throughout the entire seat construction. The seat structures throughout the car are preferably metallic, the fixed section of each seat comprising a metallic plate 17, forming the seat proper, the side edges of which are projected to form marginal guideways 18, preferably provided by bending the edges of the seat proper to form a depending right-angle wall 19 and an inwardly-extending wall 20, spaced from and in parallel relation to the seat-plate 17, the wall 20 terminating comparatively short distance from the wall 19. The telescopic section of each seat

65 ginal edges of which are bent to provide a depending wall 22 and an inwardly-extending wall 23, providing a guiding projection of a size to fit within the guideway 18 in the fixed section. The depending walls 19 of the guideway 18 are formed with guide-slots 24 extending longitudinally thereof, with which slots rivets or bolts 25, projecting from the depending wall 22 of the telescopic section, are designed to co-operate, thus permitting 70 and guiding the movement of the telescopic section relative to the fixed section.

To insure the seat-plate 21 lying in the plane with the seat-plate 17 when the sections are at their limit of extended movement, 80 the slot-walls at the end of the guide-slot adjacent the telescopic section are inclined upwardly at 26, and underlying said inclined portion 26 the wall 20 of the guideway is also upwardly inclined at 27. The wall 23 of the telescopic section is offset or downwardly inclined at 28 adjacent the connected end of said section, the seat-plate 21 of this section being also downwardly inclined at 29 above the inclined portion 28 of the wall 23. The free edge of the plate 17 adjacent the end of the telescopic section is beveled at 30 to co-operate with the inclined portion 29 of the seat-plate 21 of the telescopic section. By this construction as the telescopic section is 90 drawn from the fixed section the bolt 25, riding in the inclined portion 26 of the guide-slot, and the inclined section 28 of the wall 23, riding upon the inclined portion 27 of the wall 20, causes the telescopic section to be 100 elevated as a whole to aline its seat-plate 21 with the seat-plate 17 of the fixed section, the bevel portion 30 of the seat-plate 17 co-operating with the inclined portion 29 of the seat-plate 21 to avoid obstruction and provide a practically continuous seat-plate.

The section 14 of the forward end seat 10 may be constructed in any preferred manner, though preferably of a construction similar to that described for the fixed section 16, omitting, of course, the guide-slots and inclined ways described. When fully extended, the end of the telescopic section 15 engages the proximate end of the section 14 by fitting within the guideway 18 in said section 14, thereby securing the sections in position 115 to form a seat extending entirely transverse the car, it being understood that the forward end 5 of the car provides a back for this end seat.

The sections 14 and 16 are hinged to the approximate ends of the car by any desirable type of hinge connection 31, and each section is provided at its free longitudinal edge with a leg 32, having the hinged connection with the sections and extending to an incline therefrom, with its foot resting on the floor of the car and within a guideway 33. The foot or free end of the leg 32 is formed with a projection 34, designed to engage in rear of an off- 125

set 35, formed in the base-wall of the guide-way, said offset being positioned to support the sections in elevated or folded position, as hereinafter described.

5 The seat 11, hereinafter termed the "rear-end" seat, is illustrated more particularly in Figs. 7 and 8, wherein it is shown as comprehending a seat proper, 36, of the full width of the car and supported to provide for its movement, as hereinafter described. As this seat is contemplated for use in converting the car into a closed car, it is provided with a back 37, having hinged and reversible connection with the seat 36 through the medium of hinge-brackets 38 of the usual construction. The seat 36 and back 37 are of the sectional formation illustrated and described in connection with the seat 10, the back plate of the back 37, however, being 20 preferably longitudinally slotted to provide a series of bars 39 for lightness and comfort. At one end the seat 11 is provided with a fixed leg 40, depending from the seat and resting upon the floor of the car-body. At 25 the opposite end the seat 11 is pivotally and slidably connected with the car-body through the medium of a lug-bracket 41, revolvably supported on a rod 42, provided with upper and lower sleeves 43 and 43', mounted for 30 sliding movement upon rods 44', secured in spaced relation to the rear end of the car. The lower sleeve 43' is provided with an upwardly-extending sleeve 45', having an upper cam-surface to receive and coöperate with the cam-surface formed on the lower face of the bracket-sleeve engaging the rod 42, as 35 clearly shown in Fig. 8, for a purpose to be hereinafter explained.

The seat 12 immediately in rear of the forward seat 10 also comprises three sections 44, 45, and 46, the central section 45 telescoping within the fixed section 46 in the manner described in connection with seat 10, it being understood that the backs 47 of these respective sections are constructed practically identical with the seat portions and telescope in exactly the same manner. As will be seen particularly in Figs. 3 and 4, the sections 44, 45, and 46 are practically of 50 equal length, each including about one-third the full length of the seat when in use in the open type of car. The end of the fixed section 46 is revolvably supported in a manner similar to that illustrated in Fig. 8, the brackets 48 projecting from the floor of the car and from the adjacent roof-standard 9. The opposite end of the fixed section 46 is provided with a relatively fixed leg 49. The end of the section 44 next the telescopic section 45 is provided with a leg 50, similar to the leg 49, except that it has hinged connection with the section. The back-sections 47 of this seat are connected with the seat-sections by the usual reversible hinge-brackets 51, the bracket 51 of the section 46 being secured

to the seat-plate thereof and movable with said section, while the hinge-bracket of the connection 44 is secured to the approximate roof-standard 9 and has a hinged connection with the back 47 of this section, so that when the section 44 is turned to convert the car into a closed car the bracket 51 connected therewith remains in relatively fixed relation with the adjacent roof-standard, the necessary movement of the back 47 of this section 44 being permitted by the described hinged connection between the back and hinge-bracket thereof.

It is to be particularly noted that the swinging sections are supported on a sectional sleeve, the contacting faces of which are provided with regular cam-surfaces 48', so constructed that as the seat is swung from closed to open position, or vice versa, said seat will be slightly elevated from its normal position during such movement, thereby avoiding dragging or contact of the parts with the floor.

In converting the car from an open car to a closed car, as will be later described, it is necessary that in moving the section 44 of the seat 12 from a position transverse the car to a position longitudinally thereof that said seat when in the latter position occupy a plane below its normal plane when transverse the car. This will be readily understood, as the seat-surface of the open car is greatly in excess of that required for the closed car. Hence a portion of said seat-surface must be disposed of in converting the structure to a closed car, and in the particular section 44 it is moved into such a plane longitudinally of the car as to permit a second seat to overlie the same and provide the seat proper. This movement of the section 44 is gained primarily by securing the end of said seat next the roof-standard to a leg-bracket 52, provided with sleeves 53, designed for revoluble support on a rod 54, mounted in brackets 55, fixed, respectively, to the floor of the car and to the adjacent roof-standard 9. The sleeves 53, as well as the sleeves of the brackets 55, are formed with cam edges 56, so arranged that when the section 44 is in position transverse the car the respectively highest points of said cam-surfaces are in contact, supporting said section in a plane with the sections 45 and 46. In turning the section 44 longitudinally of the car, however, the extreme lowest points of said cam-surface are brought into contact, thereby permitting the movement of the section as an entirety into a plane below that occupied when transverse the car. By virtue of the hinged connection of the leg 50 with the section 44 said leg may be suitably inclined in moving the section 44 to its longitudinal position to support the free end of said section at the desired elevation from the floor.

The remaining seats 13 of the car, of which

there may be any desired number, are identical in construction, each comprising a fixed section 57 and a telescopic section 58. These seats are particularly illustrated in Figs. 5 and 6, wherein it will be noted that the seat-plates 59 of each section are arranged for telescopic connection, as described, and shown in Figs. 16 and 17, the back 60 of the sections being also arranged for similar telescopic connection. The fixed section of each of the seats 13 has movable connection with the adjacent roof-standard, said connection 61 being identical with that described for the seat 11 and shown in Fig. 8. The opposite or inner end of the fixed section is provided with a relatively fixed leg 62, supporting the end of this section in proper relation to the floor. The back 60 of the fixed section has hinged connection with the seat-plate 59 thereof through the heretofore - described hinge-bracket 63, the support for which is secured to the seat-plate of the section.

The free or outer end of the telescopic section of the seat 13 is designed to rest upon a horizontal ledge 64, projecting from a leg 65, fixed to the adjacent roof-standard by a suitable bracket 66, preferably also secured to the floor, as clearly shown in Fig. 6. This leg 65 also supports the hinge-bracket 67, by which the back of the telescopic section is arranged for hinged and reversible connection with the seat. As the bracket 67 is fixed relative to the adjacent roof-standard and the back-plate 60 of the telescopic section is adapted for movement away from said roof-standard, the parts must be arranged to permit ready disconnection. This result is gained by forming the end bar of the hinge-bracket with a series of openings 68 and forming the free end of the back 60 of the telescopic section with projections 69, designed to snugly fit into the openings 68 and projecting beyond the surface of the hinge-bracket. A spring-latch 70 is arranged on the face of the bracket 67 and formed with a projection 71 to enter an opening 72, formed in one of the projections 69, whereby to lock said back-plate 60 to the hinge-bracket when the parts are in co-operative relation.

It is to be particularly noted that, as shown in Fig. 1, the sections of the respective seats 13 are successively oppositely positioned—that is, the fixed section of one seat 13 will be in alignment longitudinally of the car with the telescopic section of the next succeeding seat, whereby said fixed sections are connected alternately to the adjacent roof-standards on opposite sides of the car.

Assuming the seats arranged in the manner illustrated in Fig. 1, wherein the car is of the open type, and that it is desired to convert the car, so far as the seat structure is concerned, into a car of the closed type, the 65 operation is as follows: The section 15 of the

seat 10 is telescoped within the section 16. The sections 14 and 16 are swung upwardly on their hinged connections 31, the lower end of the leg 32 engaging in rear of the projection 35, and maintaining said sections 70 elevated. The section 45 is telescoped within the section 46, and said section 46 is turned on the connection 48 toward the forward end of the car until the section rests longitudinally of the car. The section 44 is 75 turned on the connection 54 toward the front of the car, being thereby moved into a plane below its normal plane.

The sections 58 of the seats 13 are telescoped within the sections 57 and each of said 80 sections turned upon their pivotal supports toward the front of the car to cause said sections 57 to respectively align longitudinally of the car. The fixed section 57 of the seat 13, immediately in rear of the seat 12, has 85 pivotal connection with the roof-standard on the same side of the car as the section 44 of said seat 12, and the length of the section 58 of the particular seat 13 is of a length to extend approximately to the front wall 5 of the 90 car when turned longitudinally thereof, so that in the movement of this section 57 it will overlie the depressed section 14 and provide a seat extending from its pivotal connection to the forward wall of the car-body. 95 The next succeeding seat 13 has its fixed section pivotally supported on the opposite side of the car and when turned into longitudinal relation with the car will fill the space between its pivotal connection and the 100 pivotal connection or approximate end of the fixed section 46 of the seat 12. The sections 57 are thus alternately turned to opposite sides of the car to provide longitudinally-arranged seats, as clearly shown in Fig. 2. 105 As the fixed section 57 of the seat 13 immediately forward of the seat 11 is pivotally supported on the side of the car opposite the pivotal support of said seat 11, the latter seat is utilized to fill the space of the car opposite 110 the particular section 57, this result being gained by swinging the seat 11 on its pivotal connection 42 and at the same time sliding the sleeves 43 and 43' longitudinally on the rods 44' until they are positioned at the 115 opposite ends of said rods, so that the end of said seat 11 against the side of the car when in open position is caused to abut against the rear end of the car when in closed position. This operation positions the seat 11 in a 120 plane with the seat-plates of the sections 57 of the seats 13 on that side of the car, it being understood that in this movement of the seat 11 the back 37 thereof is swung upon the hinge-bracket 38 to reverse its position, 125 for an obvious reason. As thus arranged a space is left between the pivotal connection of the section 57 of the seat immediately forward of the seat 11 and the end of the car, and to fill this space an auxiliary seat 73 is 130

provided having a hinged connection 74 with the car-body opposite to the hinged connection 42 of the seat 11, said hinged connection 74 being identical in construction with that described for the section 44 of the seat 12 and so arranged that when the seat 73 is in inoperative position, which is against the rear wall of the car-body and beneath the seat 11, said seat 73 will be depressed to a plane below its normal plane, as clearly shown in Fig. 7. The free end of seat 73 is provided with a hinged leg 75, similar to that of the section 44, and the seat-plate 76 of this seat is provided with a back 77, having such hinged connection with the seat-plate as will permit the back to be turned wholly beneath the seat-plate, as clearly shown in Fig. 9. Any desired form of latch 78 may be provided for securing the back and seat-plate in relatively fixed and operative relation when desired. As stated, when the seat 11 is in a position transverse the car the seat 73, owing to its pivotal connection, is in a plane below the plane of the seat 11 and rests against the rear wall of the body and is concealed by said seat 11. In converting the car to that of the closed type, however, the seat 73, after the described movement of the seat 11, is turned in the opposite direction and arranged longitudinally of the car-body, this movement of the seat 73 on the revoluble support 74 causing said seat to move into a plane in alignment with the section 57 of the immediately-preceding seat 13, as will be obvious. The back 77 is of course turned to operative position for use with the seat when in longitudinally-arranged position.

The backs of the respective seats are held in operative or elevated position by latches 77', adapted for free vertical movement and engaging when in lowered position keeper 78', formed on the seat-plates, all as clearly shown in Fig. 15.

By arranging the seat 11 for a sliding pivotal connection with the car I am enabled to provide a seat which in an open type of car is of a length coextensive with the width of the car-body, and it is to be understood that, if desired, this seat may be of the telescopic type described in connection with the other seats, though such is not regarded as material. Provision is thus made for adjusting the seats arranged transverse of the car when of the open type to positions extending longitudinally of the car adjacent the side walls thereof whereby to provide the conventional seat arrangement of the car of the closed type.

In the closed type of car entrance is gained to the interior thereof through a door 6, while in the open type of car entrance is gained through the sides of the car between the roof-standards 9. With this arrangement desirable means must be provided for closing the sides of the car in converting the

same to the closed type and removing said closure in converting the car to the open type.

To accommodate the particular construction forming this part of my invention, the roof-standards 9 are preferably hollow, the side walls being formed of any suitable material and the end walls 79 preferably of metal and extending throughout the length of the standards. Each of these end walls 75 are suitably bent or otherwise formed to provide a series of grooves or guideways 80, 81, 82, and 83, preferably coextensive in sectional dimension, but of different lengths, the channel 83 preferably extending throughout the length of the standard, while each of the others are respectively proportionately reduced in succession, so that the guideway 80, which is arranged next to the outer wall of the standard, is shortest in length, while channel 83, arranged next the inner wall of the standard, is of greatest length, as clearly shown in Figs. 21 and 22. A series of panels 84, 85, 86, and 87 are arranged for co-operation with the respective guideways, the panels 90 of any particular series being arranged to co-operate with the guideways of the rear wall of one roof-standard and of the forward wall of the next succeeding standard, whereby to close the space between said standards when the panels are in lowered position. Each of the panels comprise a rectangular frame 88, the vertical side edges of which are embraced between the parallel flanges 89 of a guide-strip 90, which strip beyond said side edges 100 is provided with a projecting tongue 91, designed to enter the proper guideway in the walls 79 of the roof-standard. By preference the guide-strip 90 is formed of a single strip of material bent centrally upon itself to 105 provide the tongue 91 and projected laterally in opposite directions from the terminal of said tongue for a short distance, being then projected forward parallel to the tongue to provide the spaced parallel flanges 89, designed to receive the side strips of the frame 88.

The panels are supported for movement in the respectively-aligned guideways of the adjacent roof-standards, said panels 84, 85, 86, 115 and 87 co-operating, respectively, with the guideways 80, 81, 82, and 83. The respective grooves terminate relative to the floor of the car to so limit the downward movement of the respective panels as to provide 120 for completely closing the space between the roof-standards throughout their length, as clearly shown in Fig. 18. The respective panel-frames 88 are designed to support any ornamental filling strip or plate, that for the upper panels 84 and 85 being preferably of glass to afford the desired light when the car is converted into the closed type. The upper and lower edges of the frames 88 of the panels 84, 85, and 86 are provided with strips 92, 130

extending throughout the length of but of greater width than said frames, whereby to provide projecting portions 93, arranged beyond the plane of the frames and adapted to be successively contacted with by similar portions on the next adjacent frame, whereby to elevate and depress the frames in succession. The lower section 87 is provided with a similar strip 92 upon its upper edge 10 only, as will be clear from Fig. 22. A sealing-strip 94 is preferably secured to each of the panel-frames immediately above and resting upon the projection 93 at the lower edge of said frame, whereby to render the connection between the frames when in lowered position air-tight, as will be obvious from Fig. 23. The lower section 87 is connected through suitable flexible connections 95 with weights 96, depending within the respective 20 roof-standards, whereby to compensate for the weight of said section and assist in the operation of the panels.

In converting the car from the open type into the closed type the panels are moved 25 into lowered position, as illustrated in Fig. 16, by drawing downward upon the panel 87 until its lower end contacts with the floor. In the downward movement of this panel the projecting edge 93 of the strip 92 on its upper 30 edge will contact with the sealing-strip 94, supported on the projection 93 of the panel 86, drawing said panel downward until limited by contact with the lower wall of the guideway 81. The panel 86 will similarly 35 draw down panel 85 and the latter likewise operate panel 84, thus completely closing the space between the respective roof-standards and providing the car with wholly-inclosed sides. In converting the car from the closed 40 type to the open type the lower panel 87 is elevated, the projection 93 thereof contacting with the projection 93 on the upper edge of the panel 86, elevating said panel and similarly elevating the panels 85 and 84 until all 45 the panels arranged in practically transverse alignment are positioned at the extreme upper end of the respective roof-standards, thereby providing an uninterrupted opening between the roof-standards and affording 50 convenient entrance to the seats within the car.

In converting the seat structure from the closed type of car to that of the open type the operation is the reverse of that previously 55 described in converting from the open type to the closed type, and it is believed to be fully obvious from the above detailed description, taken in connection with the drawings.

60 If desired, a suitable receptacle, as 97, may be supported from one of the end walls of the car-body next the roof, in which cushions for use with the seats when the car is converted into the closed type may be stored during the 65 use of the car as an open car.

Having thus described the invention, what is claimed as new is—

1. A car comprising a body, and seats movably connected to the body and adapted to be arranged transversely or longitudinally of the body, a portion of said seats being arranged directly beneath other of said seats when in longitudinal engagement. 70

2. A car comprising a body, and seats movably connected to the body and adapted to be arranged transversely or longitudinally of the body, the seats being alternately connected to opposite sides of the body, whereby in their longitudinal arrangement they may be arranged adjacent both sides of the car- 80 body. 75

3. A convertible car comprising a body, and seats movably connected to the body, said seats comprising telescopic sections adapted when extended to project transversely of the car-body and when in telescoped relation to provide an endless seat arrangement extending longitudinally of the car. 85

4. A convertible car comprising a body, a plurality of seats movably connected to the body and adapted when arranged transversely thereof to provide the seating arrangement of a car of the open type, a number of said seats less than the whole being 90 adapted to be turned longitudinally of the car and provide the seating arrangement of a car of the closed type, the seats not in use in the longitudinal arrangement being arranged in a plane beneath the seats in use. 95

5. A convertible car comprising a car-body, a plurality of seats movably connected with the car and adapted to be arranged transversely thereof, one of the seats comprising two fixed sections and a movable section 100 telescoping with one of the fixed sections, said fixed section having hinged connection with the car-body and adapted to be turned up into contact with the same when not in use. 105

6. A convertible car comprising a car-body, a plurality of seats movably connected with the car and adapted to be arranged transversely thereof, one of the seats comprising two fixed sections and a movable section telescoping with one of the fixed sections, said fixed section having hinged connection with the car-body and adapted to be turned up into contact with the same when not in use, and means for maintaining said section in 110 elevated position. 115

7. A convertible car comprising a car-body, and a plurality of seats having movable connection with the car-body, one of said seats comprising two fixed sections and a telescopic section, the fixed sections having movable connection with opposite sides of the car-body respectively and being adapted to be arranged transversely of or longitudinally of the car-body, one of said connections op- 120 125 130

erating to move the fixed section into a plane below the normal feeding plane when said section is arranged longitudinally of the car-body.

5 8. A convertible car comprising a car-body, end seats supported by the body, and a plurality of seats arranged intermediate the end seats and respectively connected in succession to opposite sides of the car-body, each of 10 said latter seats comprising duplicate sections pivotally connected to the car-body and telescopic sections connected with one of said duplicate sections.

9. A convertible car comprising a car-body, 15 end seats supported by the body, and a plurality of seats arranged intermediate the end seats and respectively connected in succession to opposite sides of the car-body, each of 20 said seats comprising a fixed section having connection with the car-body and a telescopic section arranged for removable connection to the opposite side of the car-body.

10. A convertible car comprising a car-body, end seats connected therewith, and a 25 plurality of seats connected to the car-body intermediate the end seats, one of the end seats being hinged to the car-body to permit its being folded thereagainst when not in use, and the remaining end seat being movably 30 connected to the body to permit its arrangement transverse or longitudinally of said body, one of the intermediate seats comprising independent sections connected respectively to opposite sides of the car-body and 35 adapted to be arranged transversely or longitudinally of said body.

11. A seat structure for convertible cars comprising a fixed section formed with a guideway at each side edge, a sliding section 40 mounted for telescopic movement in the guideway of the fixed section, and means to move the sliding section into a plane with the fixed section when the sections are fully extended.

45 12. A seat structure for convertible cars comprising sections constructed wholly of metal, the side edges of one section being bent to form guideways, the side edges of the other section being bent to form guides

adapted for movement in the guideways, the 50 walls of the guideways being formed with guide-slots, and pins projecting from the guides and working in said slots, the walls of said slots and the adjacent walls of the guideways being inclined to coöperate with the 55 guides and move the sliding section into a plane with the main section when said sections are extended.

13. A convertible car comprising a car-body, hollow roof-standards forming part of 60 said body, and side walls for said body arranged in sections and slidably mounted in offset planes in the standards, each of said sections coöperating with the adjoining sections to insure relative operation of all sections 65 through movement of one section, and means for counterbalancing the lower section.

14. A convertible car comprising a car-body, hollow roof-standards forming part of 70 said body, metallic strips forming the end walls of said standards and provided with guideways, side walls for the body arranged in sections mounted respectively in the guideways, interengaging means carried by the respective sections whereby to insure the operation 75 of all in the complete operation of any one, and a counterbalancing means for the lowermost section.

15. A convertible car comprising a car-body, hollow roof-standards forming part of 80 said body, metallic strips forming the end walls of said standards and provided with guideways, side walls for the body arranged in sections and slidably mounted in the guideways, the ends of the respective sections 85 being provided with projections for engagement in the operation of the sections, the sections intermediate the upper and lower section being provided on each end with said projections, and a counterbalancing means 90 connected to the lower section and movable within the hollow standard.

In testimony whereof I affix my signature in presence of two witnesses.

WALTER ALLEN JACOBS.

Witnesses:

BURTON E. BAILEY,
A. M. CLARK.
